WELLHEAD EQUIPMENT

Robert A. Mueller and John R. Yancey, Houston, Tex., assignors to Gray Tool Company, Houston, Tex., a corporation

Application June 15, 1935, Serial No. 26,710. 9 Claims. (CL 166—15)

Our invention relates to apparatus for and methods of completing and equipping wells.

In the drilling of deep wells for oil, gas, sulphur and the like it is necessary to perform such operations as setting casing, screen, packers, tubing, and the like, or to run tools into the well for different purposes. This has frequently to be done when gas pressure in the well has been encountered and danger of blowout is present. To perform these operations, various types of well equipment are now employed. But, with present equipment, it is necessary when the changes in equipment are made, to either kill the well with mud to prevent possible blowout or to employ master valves, blowout preventers and the like, which, when once used, must be left in position on the well and are of no more value. They cannot be removed from the well without danger and are lost for use thereafter. For example, when one string of casing is being set within another string, previously set, the new casing is introduced through a blowout preventer and a master valve into proper position and properly supported and sealed at its upper end, but when this job has been completed the master valve cannot be salvaged to be used as an accessory in subsequent operations, but must be left on the casing head equipment.

Further, in all wellhead equipment work it is fundamental or of first importance where the well is under pressure to consider the areas on the equipment against which the well pressure exerts itself. Obviously, it is of material advantage to be able to perform operations with accessories of reduced diameters. It is not uncommon to encounter pressures of several thousand pounds per square inch, and thus each additional inch of exposed surface becomes important. The accomplishment effected in reducing the areas exposed to well pressure on accessory equipment required during the performance of drilling in, running tubing under pressure, etc. is entitled to first consideration, because it makes possible the holding of pressures which could not otherwise be restrained.

It is a fact that numerous patents and sales catalogues disclose cases of pyramiding accessories above the casing or tubing head, and providing the ability to hang through and remove these accessories from the well after they have performed their operation. On the other hand, it is apparent, without question, that, while these methods were well known, because of the attendant danger in their use, they have not been practiced by the trade, notwithstanding that

the ability to use equipment and in turn remove it and relegate it to the position of accessories would have effected savings amounting into hundreds of thousands of dollars. The fact that all operators have continued in the practice of tying these expensive parts permanently into each individual assembly at an enormous cost, proves without question that the dangers coincident to the use of enlarged pressure chambers in the accessories create dangers which make them impractical for the performance of this work.

It is an object of the invention to provide a structure of casing support which is adapted to pass through such devices as blowout preventers and master valves to a supporting position below them, and will then seal below such devices in such manner that the said devices may be removed and saved for subsequent operations.

By so doing we obtain several beneficial results; by being permitted to remove these structures from above the casing head we are enabled to use the devices repeatedly thereafter. Further, the amount of casing head equipment necessary upon the well being thus decreased, the depth of the cellar below the derrick platform can be materially lessened, and the expense for providing space for the equipment ordinarily necessary need not be so great.

We also desire to simplify the operations necessary in making changes from one form of equipment to another under pressure.

It is another object of the invention to provide a superior type of sealing means for the upper end of a string of pipe supported in the well.

It is a further object of the invention to provide a shorter and more sturdy equipment for the wellhead so that the various connections will not be weakened when subjected to a bending moment between the usual individual parts which have to be used.

Other objects and advantages of the invention will be explained hereafter in connection with the drawings wherein the device is disclosed.

In the drawings, Fig. 1 is a side view partly in section through the casing head showing the use of my invention in a completed well.

Fig. 2 is a side elevation showing the casing head equipped with master valve and blowout preventer.

Fig. 3 is a central longitudinal section through a casing head equipment showing the manner in which various strings of pipe may be sealed in position.

Fig. 4 is a side view partly in elevation and

partly in central longitudinal section showing one step in the equipment of the wellhead.

Fig. 5 is a similar side elevation partly in section illustrating the assembly of parts which 5 may be employed in equipping the well; and

Fig. 6 is a sectional detail of the upper end of a wellhead showing the manner in which the tubing may be supported in the casing head without other attachments.

10 This application is a continuation in part of our prior application Serial No. 756,654, filed December 8, 1934.

With reference particularly to Figs. 2 and 4, it is customary when a well has been drilled 15 downwardly for a distance of several hundred feet to set a string of surface casing which may be indicated at 1 in the drawings. At the upper end of this casing is a casing head 2 having one or more ports 3 therein through which fluid may 20 be delivered to or from the well. The upper end of the casing head is provided with a lateral flange 4 whereby a sealing connection may be made with the adjacent flange 5 of another piece of equipment. The interior of the casing head is prefer- 25 ably provided with a tapered seat indicated at 6 in Fig. 4 to receive a tapered bushing or hanger 7 upon the next inner string of pipe 8.

The drilling operation will then proceed downwardly through the casing head 2 until it becomes 30 desirable to set another string of casing. Sometimes this may be several thousand feet and during this period gas under considerable pressure may be encountered. When therefore, due to caving formation or otherwise, it becomes necessary 35 to set the next inner string of casing 8, the casing head must have been equipped with the usual master valve and blowout preventer.

In Fig. 2 the master valve 9 is shown as supported upon the casing head and secured thereto by a flanged connection. Above the master valve 40 9 and secured thereto by the flanged connection 10 is a blowout preventer 11 and it may be understood that this blowout preventer is of the conventional form with opposite rams thereon adapted to engage the drill stem in drilling. The 45 flanged connection is a preferred form of connection, or means of attachment, of one piece of equipment with another, for it enables the operator to maintain the same size of inner package throughout the assembly. In same size connections we mean that the flanged or threaded connections are not larger than are generally used by the trade with the size pipe upon which they are employed, according to accepted standards. Above the master valve is a flared nipple 12 to 50 protect the blowout preventer when the bit is inserted downwardly through the blowout preventer and master valve into the well for drilling purposes. The blowout preventer is ordinarily equipped with two lateral outlets 13 below the 55 rams.

When therefore the next inner string 8 is to be set the drill stem and drill bit are drawn upwardly out of the well until the drill bit has 60 passed the master valve 9. The blowout preventer still maintaining a seal around the drill stem, no blowout may occur. The master valve 9 is then closed after which the blowout preventer 65 may be opened to allow the bit to be drawn upwardly out of the way.

70 The next step is to insert the next string of casing. To accommodate the casing, which is larger than the drill stem, the rams in the blowout preventer must be changed to fit the casing. As will be noted from Fig. 4, this string of casing 75 8 is equipped at its upper end with a hanger 7.

Said hanger is threaded interiorly at its upper and lower ends and its lower end is provided with an outer thickened wall which is tapered downwardly to fit the seat 6 of the casing head. There are preferably sealing rings of rubber, or the like, 14 5 in the outer surface of the hanger so that when the hanger is in position a seal will be provided between the casing string 8 and the casing head 2. When this casing is inserted it is to be understood that the lower end is equipped in the usual manner with a float shoe or back pressure valve which prevents the gas from the well from escaping upwardly through the same. The hanger 7 is sufficiently small so that it may pass through the blowout preventer and master valve and seat 15 within the casing head. When thus seated the casing string will hang supported in the casing head with the lower end thereof closely adjacent the bottom of the well so that it may be cemented at the lower end. This will permit the string to 20 hang taut while the cementing operation is performed which seals about the lower end of the casing string.

An important feature of our invention may now be noted. With the string of casing thus supported in the well through the master valve and blowout preventer as described, the hanging of the inner string 8 in the casing head seals the space between the outer string 1 and the inner string 8, so that no gas can escape about the 30 inner string. The valve in the inner string prevents blowout through the same and the well is sealed against escape of pressure.

It is then possible to remove the upper equipment including the master valve 9 and the blowout preventer 11, or equivalent control accessories, so that the upper end of the well will appear approximately as shown in Fig. 6, sealed against escape of pressure. This is an important feature as it permits the repeated use of the control accessories, such as the master valve and the blowout preventer. In the equipment of wells as previously carried out, it has been necessary to leave the master valve 9 upon the well for the reason that the next inner string had to be supported above the master valve, making it impossible thereafter to remove the same, and the control accessories then became a permanent part of the outer string of casing and was of no further use to the operator.

The next step in the finishing of the well is to attach above the casing head 4 a second casing head 15, the lower flange 5 of which will be secured to the casing head as previously noted. A seal is made between the casing head 15 and the hanger 7 by means of a metal gasket shown at 16. It will be noted that the weight of the second casing head is clamped against the hanger so that it is thereafter fixed firmly in position. The second casing head 15 has a slightly smaller 60 seat 6' therein to accommodate the next string of casing and it will be noted that the opening through the second casing head 15 is of the same interior diameter as the casing string 8 previously set.

Where the opening through the casing head, blowout preventer, or the like, is the full diameter of the casing through which further drilling or other operations must proceed, we call it a "full opening" casing head or a "full opening" gate 70 valve or the like. There is no constriction presented which would hinder the introduction of tools the full size of the interior of the casing string. The connections between casing heads, blowout preventers, valves and other fittings at 75

the wellhead are the same size, that is, the flanged or threaded connections are not larger than would generally be used with a given size pipe for a given pressure in manifolding and pipe connection work according to accepted practice. We also employ an adapter 17 between the casing head 16 and the lower end of the master valve 9, which is mounted above the casing head in the same manner as shown in Fig. 2. When the master valve and blowout preventer shown in Fig. 2 are then assembled in place, the drilling may proceed.

The drill and drill stem are inserted downwardly through the blowout preventer and valve 9 and when the bit has passed the blowout preventer the rams may close about the drill stem to seal therewith during the drilling operation, the rams of the blowout preventer being changed to accommodate the diameter of the drill stem. The float valve will be drilled out and the well may be extended further downwardly as desired. It will be obvious that as many strings of casing may be set as desired, and in each case the use of a hanger similar to the hanger 7 previously noted, on the string of casing which is set, will not only serve to form a seal when in position but will enable the driller to hang the inner string and set the same so that the equipment above the hanger may be thereafter removed and other pieces of equipment attached to the well head without danger of blowout.

Thus, in Fig. 1, the upper end of the casing head is equipped with a reduced nipple 17 to which a valve 18 and flow line 19 are connected. It will thus be possible to provide above the flow line 19 any form of Christmas tree or other equipment desired. I have shown a branch line 20 with other lines connected by means of a cross 21 thereto. The upper end of the flow line is shown as being closed by a bull plug 22 having a vent 23 thereon.

In Fig. 5, I have shown another form of equipment in which the hanger, the upper end of which is shown at 7, is clamped in position by a plate 24, the outer margin of which is bolted to the flange 4 of the casing head. The upper threaded end of the bushing 7 has a pipe 25 connected thereto in which is secured a tubing head 26. The upper end of the tubing 27, which is supported in the tubing head, has a tapered bushing or hanger 28 thereon with lateral arms 29 for engagement by an elevating means.

In Fig. 3 a different form of hanger is shown which enables the operator to obtain a close seal at both ends of the hanger without the necessity of a packing gasket between the flanges of the parts. Thus it will be seen that the second string of casing 8 has a hanger 7' thereon, the lower end of which is formed in the same manner as the hanger 7. However, the upper end is extended somewhat and is provided with an upper tapered end 30 which is adapted to fit within an inner tapered seat 31 in the casing head 15'. It will be obvious that when the casing head 15' is bolted and clamped downwardly against the upper end of the casing head 2 the hanger will form a seal with both casing heads, thus preventing leakage along either of the ends thereof. A similar bushing 7" may be employed at the upper end of the next inner string of casing. In this way each string of casing may be supported in the casing head structure and provide a full opening downwardly therethrough so that a drill bit or other tools may be lowered directly downwardly therethrough during the drilling operation. When the

well has been completed the upper casing head section 32 will act as a support for the hanger 33 at the upper end of the tubing 34.

The advantages of the hanger 7' lie in the fact that we are enabled to obtain a seal which will not leak in use and which is not dependent upon a packing gasket such as is ordinarily used and which is more liable to leak.

The advantages of this invention will appear from the description already given. By the use of the type of hanger which has been described each succeeding string of pipe may be suspended and supported in the casing head at a point below the point of attachment of the master valve and blowout preventer without the use of mud to hold back the gas pressure. The hanger automatically maintains a seal between the same and the casing head so that there is no danger of a blowout during the changing of the structure above the hanger. This enables us to remove the master valve and blowout preventer, or such other structure as may be connected above, so that another casing head or adapter may be connected above the casing head ready for the next step in the finishing and equipping of the well. It is further to be noted that the interior of the hanger and the casing which is thus supported provide a full opening through which the next size of drill bit and drill stem may be lowered into the well. Furthermore, the hanger is of comparatively small outer diameter. This is of advantage in that it may be lowered under heavy gas pressure with the string of pipe attached thereto through the usual blowout preventer and master valve and dropped into the seat below these parts and act to form a seal below said master valve so that said master valve may be removed. This is a feature of great importance and enables the driller to not only save equipment for further use but to economize largely in space which is required to house the devices which are connected at the upper end of the casing. The resulting well head equipment is short and compact and may be contained within a cellar at the upper end of the well which is comparatively shallow. The further advantages will be obvious to those skilled in the art.

What is claimed as new is:

1. In combination, a well casing, a lower casing head thereon, a second casing head supported above said lower casing head, a bushing threaded internally at its ends and tapered downwardly on its lower end to engage a tapered seat in said lower casing head, and having a tapered upper end to engage an upwardly tapered seat in said second casing head.

2. In combination, a well casing, a lower casing head thereon, a second casing head supported above said lower casing head, a bushing, a second string of casing supported by said bushing, said bushing being tapered at its lower end to engage a tapered seat in said lower casing head, and having a tapered upper end to engage an upwardly tapered seat in said second casing head.

3. In combination, a well casing, a full opening casing head thereon, an inner hanger seat on said casing head, control accessories mounted on said casing head, said accessories having the same size connections as said casing, a hanger to support a second string of casing in said seat, adapted to be inserted through said accessories, interior threads at the upper end of said hanger, and means on the exterior of said hanger to seal with an upper casing head.

4. In combination, a well casing, a full opening

casing head thereon having an inner diameter as large as said casing, an inner hanger seat in said casing head, control accessories connected above said casing head, the internal diameter of said accessories being no larger than the exterior diameter of said casing, an inner pipe string, a hanger therefor having an outer diameter adapted to pass through said accessories and seat in said casing head seat, interior casing threads at the upper end of said hanger, and means on the exterior of said hanger to seal with an upper casing head.

5. A casing hanger for wells including a body adapted to be lowered through a drilling control to engage a casing head, a tapered lower end on said body to engage said casing head and support the casing, packing rings mounted in the outer surface of said tapered end, means to thread a pipe to the upper end of said hanger, and 10 means on the outer periphery of said upper end to support a second casing head on said hanger and make a fluid seal therewith below the upper extremity of said hanger.

6. A pipe hanger for wells including a bushing internally threaded at its lower end, a tapered outer face on said bushing adapted to engage and seal upon a lower casing head and support a pipe threaded to said bushing, an upwardly tapered extension of reduced outer diameter upon said 15 bushing adapted to support an upper casing head having a downwardly flaring seat and form a seal therewith.

7. A casing hanger for wells including a body adapted to be lowered through a drilling control, 20 said hanger having casing threads formed at each

end thereof, a seating surface tapered downwardly at the lower end of said body to engage and seal on a supporting casing head, said hanger being reduced in outer diameter to form a shoulder above said tapered surface, and an upwardly tapered sealing surface above said shoulder on said hanger to engage and support a second casing head.

8. In combination, a well casing, a lower casing head thereon, a second casing head mounted above said lower casing head, a casing hanger separating said casing heads, a downwardly tapered lower end on said hanger to form a sealing engagement with said lower casing head, said hanger being reduced in external diameter above 15 said downwardly tapered portion to form an upwardly presented shoulder, an internally threaded upper extension above said shoulder, means on the outer surface of said extension to support and seal with said second casing head, and means 20 to secure said hanger in said lower casing head.

9. In combination, a casing head having a hanger seat therein, a pipe hanger adapted to be lowered through a drilling control and the lower end of which is tapered downwardly to fit 25 said seat, sealing means secured upon the tapered portion of said hanger, an externally reduced and internally threaded upper extension on said hanger, said extension being formed on its outer periphery to support and seal with an upper 30 casing head, and means to secure said hanger in position between said two casing heads.

ROBERT A. MUELLER.
